DOWEL STRUCTURE

Elmer J. Webb, Newark, N. Y.

Application September 20, 1947, Serial No. 775,255

2 Claims. (Cl. 94—18)

1

This invention relates to a dowel structure for joints between concrete slabs, such as joints between slabs in concrete highway construction.

The invention consists of an improvement on the dowel structure disclosed in my prior Patent No. 2,183,484, issued December 12, 1939.

These dowel structures are employed to support adjacent or confronting edges of the concrete slabs to keep the top surfaces of the slabs in alinement and at the same time, the dowel structures permit expansion and contraction of the slabs resulting from seasonal changes in temperature.

This invention has as an object an improved dowel arrangement whereby the dowel rods are more effectively supported where they protrude from the confronting faces of the slabs into the opening or space at the joint between the slabs, and whereby the medial vertically extending portion of the dowel rod positioned in the joint between the slabs is more free to flex when the rods are placed under compression and tension resulting from the expansion and contraction of the slabs.

The invention has as a further object a dowel structure by which the unit can be quickly and conveniently placed transversely of the road grade, and which includes a compressible spacer strip with a plurality of individual dowel structures positioned thereon, the normally flexible strip being rendered rigid for convenient handling and positioning.

The invention consists in the novel features and in the combinations and constructions hereinafter set forth and claimed.

In describing this invention, reference is had to the accompanying drawings in which like characters designate corresponding parts in all the views.

In the drawings—

Figure 1 is a top plan view of a dowel arrangement embodying my invention.

Figure 2 is a vertical sectional view of the structure shown in Figure 1.

Figure 3 is a view taken on line 3—3, Figure 2.

Figure 4 is a side elevational view of one of the supporting plates.

Figure 5 is an enlarged view similar to Figure 2.

The joints between the concrete slabs 10 are formed by a compressible spacer strip 11, usually of impregnated fibrous material, formed at spaced intervals along its length with apertures 12 providing openings in the joint between the slabs. A dowel structure is arranged at each opening in the spacer strip and consists of a rod having a vertically extending medial portion positioned in the space between the confronting

2

edges of the slabs, and laterally extending portions embedded in the slabs. The rods are preferably arranged in pairs with the medial portions 13 positioned in the opening 12, and with the lateral portions 14 of the rods extending from the upper part of the opening, and the lateral portions 15 extending from the lower part of the opening. One of the lateral portions, as 14, is preferably bent downwardly to form a foot portion 16 engaging the road grade to maintain the dowel structure and the spacer strip 11 in proper position while the concrete is being poured.

The opening 12 is closed by a plate 18 arranged on each side of the strip 11. These plates are formed with apertured protrusions 19 adjacent the upper and lower sides of the opening 12 respectively, and on opposite sides of the vertical medial line of the plates. The plates are also formed with an elongated depression 20 arranged in vertical alinement with each protrusion 19. The protrusions 19 merge with the plates on a radius 22.

The lateral portions 14, 15, of the rods extend through the apertured protrusions into the slabs and preferably, the radius on which the lateral portions 14, 15, merge with the radial portion 13 is greater than the radius 22.

As previously stated, the spacer strip 11 is formed with fibrous material to make it compressible when the slabs expand under temperature rise. These strips are accordingly extremely flexible and when a dowel joint unit, consisting of a strip with a plurality of dowel structures attached thereto, is moved into position on the road grade, it is difficult to handle the unit. The strip 11 fractures easily, and it takes time to line the unit up straight prior to pouring the concrete.

In the arrangement herein disclosed, I mount a channel member 23 on the lower edge of the spacer strip 11, the channel extending the full length of the spacer strip, with the side walls of the channel engaging opposite sides of the strip. The plates 18 are formed along their lower edges with one or more ribs or corrugations 24 which engage and interlock with beads 25 formed on the edges of the channel member 23.

The plates 18 are clamped against the sides of the strip 11 by a bolt 26 and with the corrugations 24 in the lower edges of the plates interlocked with the channel member 23.

With this arrangement, the spacer strip 11, with a number of individual dowel structures assembled therewith, can be quickly and conveniently positioned on the road grade, and these units are adequately supported while the concrete is being poured.

In the structure of my prior patent, the plates corresponding to the plates 18 were simply apertured to receive the laterally extending portions of the dowel rods. Their function was to hold the dowel rods in proper position until the concrete was poured, and to close the sides of the opening in the spacer strip and, of course, by the depressions in the plates, to provide a space for movement of the medial portion of the rod during expansion and contraction of the slabs. That structure has proven to be entirely satisfactory for ordinary highway construction. However, in some instances where the highway was subjected to unusually heavy truck traffic, it was necessary to use a dowel rod of larger diameter. This was due to the fact that the plates of my prior structure did not provide the maximum bearing necessary for the dowel rods to carry the greater load.

In the structure herein described, the plates 18 provide a stirrup structure which adequately supports the rods especially when they are under compression. It will be understood that downward pressure on one slab will place one rod of each pair under compression, and the other rod under tension. For example in Figure 2, if downward pressure is applied to the right hand slab 10, the medial portion 13 of the rod, shown in section, will be under compression, and the medial portion of the other rod, shown in elevation, will be under tension. The bar, under compression, bears against the outside portion of the protrusions 19, the plates acting as stirrups and, inasmuch as they are embedded in the concrete, take the major portion of the load off from the concrete surrounding the lateral extensions 14, 15, of the rod. This results in obtaining the maximum compressive and tensile strength of the rods at the road joints, whereby rods of the same diameter effectively carry a much greater load without failure of the rods, or failure of the concrete in the confronting faces of the slabs.

The plates 18 are embedded in the concrete slabs and inasmuch as the protrusions 19 extend into the slab, this critical point of bearing is located within the slab. In view of the fact that the radius 22 of the protrusions is less than the inside radius at the bend of the rod, this allows a slight straightening of the bar at the radius, rather than stretching the metal and thus causing serious stresses in the bar and, at the same time providing a continuous bearing for the bar at the portion under tension during the complete cycle of expansion and contraction of the slabs.

What I claim is:

1. A pavement joint dowel structure supporting adjacent slabs of concrete comprising a spacer strip positioned between the confronting ends of the slabs and having an opening intermediate the upper and lower edges thereof; a plate arranged on each side of the strip in register with said opening and forming a closure therefor, said plates being embedded in the confronting faces of the slabs respectively and each of said plates being formed with a pair of apertured protrusions arranged in vertically spaced relation and extending into the slabs and merging with the plates on an arc, a pair of dowel rods, each having lateral portions extending in opposite directions from a medial portion and being joined thereto on an arc having a radius greater than the radii of said protrusions, said rods being positioned with

their medial portions extending vertically in the opening in the spacer strip and with their arcs engaging the arcs of said protrusions and with their lateral portions extending through said apertured protrusions in the plates, one of said rods having a lateral portion extending through the lower protrusion in one plate and the other rod of said pair having a lateral portion extending through the upper protrusion in said plate, the other lateral extensions of said pair of rods extending through the extrusions of the other plate in the reverse order, and each of said plates being formed with a recess arranged in register with the apertured protrusion in the other plate and forming a space within which to permit movement of the medial portions of said rods during expansion of said slabs.

2. A pavement joint dowel structure supporting adjacent slabs of concrete comprising a spacer strip positioned between the confronting ends of the slabs and having an opening intermediate the upper and lower edges thereof, a plate arranged on each side of the strip in register with said opening and forming a closure therefor, said plates being embedded in the confronting faces of the slabs respectively and each of said plates being formed with a pair of apertured protrusions arranged in vertically spaced relation and extending into the slabs and merging with the plates on an arc, a pair of dowel rods, each having lateral portions extending in opposite directions from a medial portion and being joined thereto on an arc having a radius greater than the radii of said protrusions, said rods being positioned with their medial portions extending vertically in the opening in the spacer strip and with their arcs engaging the arcs of said protrusions and with their lateral portions extending through said apertured protrusions in the plates, one of said rods having a lateral portion extending through the lower protrusion in one plate and the other rod of said pair having a lateral portion extending through the upper protrusion in said plate, the other lateral extensions of said pair of rods extending through the extrusions of the other plate in the reverse order, each of said plates being formed with a recess arranged in register with the apertured protrusion in the other plate and forming a space within which to permit movement of the medial portions of said rods during expansion of said slabs, and a reinforcing channel member positioned on the lower edge of said strip with the sides of the channel frictionally engaging the opposite sides of the strip, means operable to clamp said plates onto the strip, said plates and channel member having means cooperable to interlock the same upon operation of said clamping means.
